Primary Examiner — Brett Miller*Assistant Examiner* — Jessica M Gebhart(74) *Attorney, Agent, or Firm* — ArentFox Schiff LLP(57) **CLAIM**

The ornamental design for a tote bag, as shown and described.

DESCRIPTION

FIG. 1 is a front left perspective view of an embodiment of a tote bag showing our design;

FIG. 2 is front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1; and,

FIG. 7 is a bottom view of the design shown in FIG. 1.

The figures include broken and solid. The areas within the solid lines form the claimed design. The broken lines shown in the figures are included for the purpose of illustrating environmental structure of the tote bag and form no part of the claimed design.
